O. HEINIGKE.
CARPET.

No. 20,315.

Patented Nov. 18, 1890.

UNITED STATES PATENT OFFICE.

OTTO HEINIGKE, OF NEW UTRECHT, NEW YORK, ASSIGNOR TO THE HARTFORD CARPET COMPANY, OF HARTFORD, CONNECTICUT.

DESIGN FOR A CARPET.

SPECIFICATION forming part of Design No. 20,315, dated November 18, 1890.

Application filed October 20, 1890. Serial No. 368,751. Term of patent 3½ years.

To all whom it may concern:

Be it known that I, OTTO HEINIGKE, of New Utrecht, in the county of Kings and State of New York, have invented a new and original 5 Design for Carpets, of which the following is a specification, reference being had to the accompanying photograph, which forms a part of the same.

The invention relates to a design to be 10 worked into or upon surfaces, such as carpets or similar fabrics; and it consists in the novel configuration and grouping of figures herein specifically shown and claimed.

The accompanying photograph is a face 15 view of a carpet showing my new design.

My design consists of the body A and border B. The body A consists of groups of conventionalized flower forms having gem forms arranged in scroll-like lines and having conventionalized leaf and flower forms interspersed upon a watery-appearing ground. The border B consists of a ragged marginal border and of groups of conventionalized flower forms having gems arranged in scroll-like lines ornamented with rosettes and conventionalized leaf forms on a watery-appearing ground. The outer margin is composed of irregular-pointed ornaments. 25

What I claim is—

1. A design for carpets, consisting of the 30 body A, substantially as shown.
2. A design for carpets, consisting of the border B, substantially as shown.
3. A design for carpets, consisting of the body A and border B, substantially as shown. 35

OTTO HEINIGKE.
